UNITED STATES PATENT OFFICE

148,049

DESIGN FOR A KNIFE

Leo Caldwell, Los Angeles, Calif.

Application May 31, 1946, Serial No. 130,250

Term of patent 3½ years

(Cl. D22—3)

To all whom it may concern:

Be it known that I, Leo Caldwell, a citizen of the United States, residing at Los Angeles, in the county of Los Angeles and State of California, have invented a new, original, and ornamental Design for a Knife, of which the following is a specification, reference being had to the accompanying drawing, forming part thereof.

I claim:

The ornamental design for a knife, substantially as shown and described.

LEO CALDWELL.
